UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

HOTEL RANGE.

Application filed May 11, 1925. Serial No. 29,356.

To all whom it may concern:

Be it known that I, HENRY C. MAUL, a citizen of the United States, residing at Detroit, in the county of Wayne and State of

5 Michigan, have invented certain new and useful Improvements in Hotel Ranges, of which the following is a specification, reference being had therein to the accompanying drawings.

10 This invention relates to hotel ranges of that type disclosed in my Patent No. 1,480,407, dated Jan. 8, 1924, wherein a cooking top and oven have separate sources of heat supplied by gas burners, there being one set

15 of burners for the cooking top and another set of burners for the oven. This is one instance of where a cooking top and oven have separate gas burners, and I have in mind another instance where the width of a

20 range is materially increased so that the gas burners for the cooking top may be at one side of the range. In this latter instance the range requires considerable space in a hotel kitchen and when a plurality of the ranges

25 are placed in battery formation considerable space is required. In both instances, the gas burners for the ovens consume considerable gas and it is in view of this fact that this invention aims to provide a hotel range that

30 is economical in its operation, there being but a single source of heat for the cooking top and oven of the range. In addition to this economical operation of the range, my invention aims to reduce the width of the

35 range to a minimum so that when placed in battery formation the ranges will occupy a minimum space in a hotel kitchen.

My invention further aims to provide a hotel range wherein a series of flues communicating with a combustion chamber are adapted to heat all of the walls of an oven, and this is accomplished with a great saving of fuel and material.

40 My invention will be hereinafter specifically described and then claimed, and reference will now be had to the drawings, wherein—

45 Figure 1 is a vertical cross sectional view of a hotel range in accordance with this invention;

Fig. 2 is a plan of the range with the cooking top removed;

Fig. 3 is a vertical longitudinal sectional view taken on the line III—III of Fig. 1;

50 Fig. 4 is a front elevation of the range;

Fig. 5 is a horizontal sectional view taken on the line V—V of Fig. 1, and

Fig. 6 is a similar view taken on the line VI—VI of Fig. 1.

The range comprises a bottom wall 1, a 60 rear wall 2, side walls 3, a front wall 4, and a cooking top 5. The walls 1, 2 and 3 are of the usual and well known construction including casings for insulation material, and below the cooking top 5 is a support 6 for 65 bricks or refractory material 7, adapted to form the bottom of a combustion chamber 8 below the cooking top 5.

Suitably mounted in the range is an oven 9 and access is had to the oven through a 70 doorway 10, in the front wall 4, normally closed by a door 11. The walls of the oven 9 are in spaced relation to the walls 1, 2 and 3 and the support 6 so as to provide a top flue 12, side flues 13, a bottom flue 14, 75 and a rear flue 15, said rear flue communicating with an exhaust box 16 and pipe 17.

The top flue 12 is the full width and length of the top wall of the oven and the rear end of said flue communicates with the 80 combustion chamber 8 through an oblong opening 18, in the rear end of the support 6.

At the front end of the combustion chamber 8 there is a group of gas burners 19 85 adapted to project their flames inwardly and upwardly against the cooking top 5 and the products of combustion are adapted to travel rearwardly and downwardly through the opening 18 into the top flue 12. In this 90 top flue are vertically disposed deflectors or partitions 20 extending forwardly and inwardly from the rear end of the flue 12 to a point adjacent the front end of the flue, so that the products of combustion must travel 95 forwardly in the flue before spreading side-wise and entering the side flues 13. This will insure a thorough heating of the top wall 21 of the oven 9 and it will be noted that the deflectors or partitions 20 connect 100 the oven wall 21 to the support 6, thus providing a rigid and substantial structure for the refractory material 7 forming the bottom of the combustion chamber 8.

In the bottom flue 14 are deflectors or partitions 22 similar to the deflectors 20 in construction and arrangement and in consequence of these deflectors the products of combustion traveling downwardly in the side flues 13 must travel towards the front of 110

the range before passing between the deflectors 22 and through a series of openings 23 into the rear flue 15. It is therefore apparent that the entire bottom wall of the oven will be heated and as the products of combustion spread out into the rear flue 15, to eventually exhaust, the back wall of the oven will be heated. The series of apertures or openings 23 serve somewhat to retard the products of combustion and it is by virtue of the novel arrangement of flues that all of the oven walls, with the exception of that formed by the door 11 are heated from a single source of heat serving the cooking top of the range. There are no burners below the bottom of the oven and therefore the lower part of the front wall 4 is devoid of gas supply pipes, valves and air mixers. This reduces the cost of manufacture and by eliminating the usual bottom burners there will be a great saving in gas, which when considering a battery of ranges is a large item.

The gas burners 19 represent a suitable source of heat for the combustion chamber 8 and the cooking top 5, and with said burners at the front of the range and within that zone between the side walls of the range, the over-all width of the range is materially reduced when comparing it with ranges having a source of heat at one or the other sides of the range.

What I claim is:—

1. A range having a cooking top and oven, a chamber under said cooking top for a source of heat adapted to heat said cooking top and said oven, a top flue between said chamber and said oven, said flue having for its top wall the bottom wall of said chamber and for its bottom wall the top wall of said oven, and flues at the bottom, sides and rear of said oven adapted to receive heat from said chamber.

2. A range as called for in claim 1, and converging deflectors in the top flue to cause the heat to travel towards the front of the range before entering the side flues.

3. A range as called for in claim 1, and converging deflectors in the bottom flue to cause the heat to travel to the front of the range before entering the rear flue.

4. A range having a cooking top and an oven, burners at the front portion of the cooking top of said range, a support between the cooking top and the oven providing a combustion chamber communicating with a top flue and in which combustion chamber the products of combustion travel rearwardly and enter the rear end of the top flue to travel forwardly therein, and a series of flues arranged to cause the heat to traverse the side, bottom and rear walls of the oven, with the rear flue having a wall forming the rear walls of the combustion chamber and the top flue.

5. A range as called for in claim 4, where in the products of combustion travel downwardly at the sides of the oven; inwardly and forwardly under the oven, and upwardly behind the oven.

6. A range having a combustion chamber, an oven, gas burners directing products of combustion rearwardly in said combustion chamber, a top flue between said oven and said combustion chamber to receive products of combustion from said combustion chamber; side, bottom and rear flues through which products of combustion travel from said top flue, and means in said top and bottom flues and set in from the side edges of the oven to cause said products of combustion to travel towards the front of said range.

In testimony whereof I affix my signature.
HENRY C. MAUL.
